UNITED STATES PATENT OFFICE.

JOHN A. ENOS, OF WASHINGTON, DISTRICT OF COLUMBIA.

GAS-GENERATING MACHINE.

SPECIFICATION forming part of Letters Patent No. 571,221, dated November 10, 1896.

Application filed September 13, 1895. Serial No. 562,368. (No model.)

To all whom it may concern:

Be it known that I, JOHN A. ENOS, of Washington, District of Columbia, have invented a new and Improved Gas-Generating Machine, 5 of which the following is a full, clear, and exact description.

This invention relates to machines of a portable character for generating gas for illuminating or heating purposes.

10 The object is to provide a machine so constructed that there will be a constant supply of air forced through the generator, which will prevent variations of the flame; and, further, to so operate the generator-cylinder that 15 all of the heavier oils will be operated upon by the air-pressure.

The invention will be fully described hereinafter and defined in the claims.

Reference is to be had to the accompanying 20 drawings, forming a part of this specification, in which similar characters of reference indicate corresponding parts in all the views.

Figure 1 is a side elevation of a gas-generating machine embodying my invention. Fig. 25 2 is a plan view thereof; and Fig. 3 is a partial section and partial elevation, on an enlarged scale, of some of the operating parts.

Referring to the drawings, A A' A² A³ designate a series of pumps, each mounted on a 30 bed-plate A⁴ and extended vertically. Each pump comprises a shell or casing 1, having a bottom closure 2, a tubular piston 3, closed at its top and operating concentrically in the shell or casing 1, an air-inlet pipe 4, open at 35 its top and arranged within and concentric with the piston and having an opening through the bottom closure 2 of the shell or casing 1, and an air-outlet pipe 5, placed concentrically within the inlet-pipe 4 and of 40 somewhat less area than the area of the pipe 4. The cylinder or casing 1 is designed to be filled with a liquid sealing material for the piston. This liquid may be water.

The inlet-pipe 4 communicates at its lower 45 end with an inlet-pipe 6 of large diameter, and which is here shown as of substantially S shape. Its upper end is provided with a valve-casing 7, having a perforated partition 8, arranged horizontally therein, and upon 50 which is mounted a valve-plate 9, which is movable upward, to admit air through the perforations of the partition 8, on a screw 10,

projected from said partition 8. This valve-plate consists of flexible material, such, for instance, as rubber, and it may be provided 55 with a weight 11 to force it downward.

The outlet-pipe 5 extends downward through the lower portion of the pipe 6 and communicates with an outwardly and upwardly extended pipe 12, having at its upper 60 portion a valve-casing 13, in which is arranged horizontally a perforated partition 14, having a valve-plate 15, of flexible material, on its upper side, movable on a pin 16, extended from the plate, and having a weight 17 for holding 65 it or forcing it to its seat. The pipes 12 of the pumps A' A³ above the valve discharge into a chamber 18, and the pipes 12 of the pumps A A² discharge into a chamber 19, and these chambers 18 19 are connected by a pipe 70 20, from which a pipe 21 extends to the generator B.

I will now describe the mechanism shown for operating the pump-pistons.

22 designates a gear-wheel rigidly mounted 75 on a driving-shaft 23, having bearings in blocks on standards 24, extended upward from the bed-plate A⁴. The gear-wheel 22 meshes with a pinion 25, mounted on a transverse shaft 26, having bearings in blocks on 80 uprights 27, extended from the bed-plate A⁴, and on this shaft 26 is mounted a gear-wheel 28, meshing with a pinion 29, loosely mounted on the shaft 23. To this pinion 29 is attached a gear-wheel 30, which meshes with a pinion 85 31, attached to a sleeve 32, adapted to rotate freely on the shaft 26. To the other end of this sleeve 32 a gear-wheel 33 is attached, and this gear-wheel 33 meshes with a pinion 34 on a sleeve 35, mounted to rotate on the shaft 90 23, and to this sleeve 35 is attached a large gear-wheel 36, which meshes with a pinion 37, mounted on a shaft 38, which carries at its ends crank-disks 39 40.

The pistons of the pumps A A² are 95 respectively connected by links 41 42 with a walking-beam or lever 43, having its fulcrum in a hanger 44, depending from a transverse bar 45 on uprights 46. The pistons of the pumps A' A³ are respectively connected by 100 links 47 48 to a walking-beam or lever 49, having its pivotal or fulcrum bearing like the one hereinbefore described.

Extended downward from the shaft of the

walking-beam 43 is an arm 50, which has a pitman connection 51 with the crank-disk 39, and the walking-beam 49 has a similar arm 52 depending from it, and this arm has a pitman connection 53 with the crank-disk 40. To regulate the throw or length of movement of the pistons, the wrist-pins 54 for each pitman are adjustable in a transverse slot 55 in the crank-disks.

10 It will be seen particularly in Fig. 1 that the crank-disks are so arranged that the wrist-pin of one crank-disk will be in a position substantially at right angles to the position of the wrist-pin on the other crank-disk. By 15 this construction it is obvious that there will be a constant operation of the pump-pistons and that at least one piston will be on the downward stroke while the other pistons are on an upward stroke, so that there will be no 20 variation in the air-pressure or flow of air carried through the generator.

Rotary motion is imparted to the shaft 23 by any suitable motor. I have here shown a drum 56, having journal-bearings in a suitable frame, and around which a cord or connection with an operating weight is placed. At one end the drum 56 is provided with a gear-wheel 57, meshing with a pinion 58, the shaft of which has a crank 59 attached to it, 25 by means of which the drum may be rotated to wind the cord when it is desired to start the machine in operation. As a means for preventing the rotation of the drum at any time, I provide it with a ratchet-wheel 60, 30 adapted to be engaged by a pivoted dog 61 on the frame.

The generator B consists of a cylinder mounted to rotate on standards 62, extended upward from the bed-plate A⁴. Arranged 40 vertically within the cylinder B are two perforated diaphragms 63 64, forming end chambers 65 66, and a central chamber 67, within which chamber a packing of absorbent material, such, for instance, as sponge in small 45 pieces, is packed. Affixed to one trunnion or journal of the generator-cylinder is a band-wheel 68, having a band 69 extended around idler-pulleys 70 and around a pulley 71, affixed to the shaft 23, so that when in operation the 50 generator-cylinder will be slowly rotated. The object of rotating the generator-cylinder is to keep the heavy oil, which would ordinarily settle at the bottom of a stationary cylinder, in constant movement through the 55 absorbent material in the generator. By keeping the oil in constant movement it will all be used in the manufacture of gas.

I find by experience that an ordinary cylinder for the generator often gets out of shape 60 by expansion and contraction due to atmospheric changes, and to obviate these diffi-

culties I have shown the cylinder B as corrugated on all its sides. The pipe 21 has a suitable valve, and this pipe 21 communicates with the interior of the generator through one 65 of its trunnions, and the other trunnion of the generator communicates with a valved outlet-pipe 62^a, and a water-pressure gage 63^a may be placed on the pipe 62.

In operation the air will be forced through 70 the pipe 21, through the perforations in the diaphragm 64, and through the absorbent material 67, containing the oil, and the gas formed therein will be forced through the perforations in the diaphragm 63 and out through 75 the discharge-pipe 62^a to the place of consumption.

The machine embodying my invention, as above described, may be operated in any locality and for any length of time, and the consumption of oil I find in this machine is comparatively small.

Having thus described my invention, I claim as new and desire to secure by Letters Patent—

1. A gas-generating machine, comprising a generator cylindrical in cross-section and having annular corrugations on its side and end walls, perforated diaphragms in the generator, absorbent material between the diaphragms, means for rotating the generator and means for forcing a constant pressure of air through the generator, substantially as specified.

2. In a gas-generating machine, a generator 95 comprising a cylinder of corrugated metal and mounted to rotate, perforated diaphragms in the said cylinder, absorbent material between the diaphragms, and means for rotating the cylinder, substantially as specified.

3. The driving power for a gas-generating machine, comprising a weight-operated drum, a shaft operated thereby, a gear-wheel rigidly mounted on said shaft, a pinion on another shaft and with which the gear-wheel meshes, 105 a gear-wheel connected with said pinion and meshing with a pinion loosely mounted on the first-named shaft, a gear-wheel connected to this last-named pinion and meshing with a pinion attached to a sleeve mounted to rotate on the second-named shaft, a gear-wheel on said sleeve connected with a pinion mounted on a sleeve adapted to rotate on the first-named shaft, a large gear-wheel on this last-named sleeve, a pinion with which this large 115 gear-wheel engages, and crank-disks on the shaft of said pinion, substantially as specified.

JOHN A. ENOS.
